[57] **CLAIM**

The ornamental design for a razor, as shown and described.

DESCRIPTION

FIG. 1 is a top perspective view of a razor showing our new design;

FIG. 2 is a bottom perspective view thereof;

FIG. 3 is a top plan view thereof;

FIG. 4 is a bottom plan view thereof;

FIG. 5 is a right side elevational view, the left side elevational view being a mirror image thereof;

FIG. 6 is a front elevational view thereof; and,

FIG. 7 is a rear elevational view thereof.

The broken lines showing the blades are for illustrative purposes only and form no part of the claimed design.
